UNITED STATES PATENT OFFICE.

SAMUEL HAMM, OF PHILADELPHIA, PENNSYLVANIA.

DESIGN FOR A TOY TARGET.

Specification forming part of Design No. **6,966**, dated October 28, 1873; application filed June 7, 1873.
[Term of Patent 3½ years.]

To all whom it may concern:

Be it known that I, SAMUEL HAMM, a resident of the city of Philadelphia, State of Pennsylvania, and a citizen of the United States, have invented a new and original Design for a Toy, of which the following is a specification:

The nature of my design is fully represented in the accompanying drawing, and is described as follows:

This design has relation to a toy target for

target practice. The design consists in the form of the object referred to, which represents the figure of a bird, A, supported on a cross-bar, B, of a bow, C, as shown in the drawing.

What I claim, and desire to secure by Letters Patent, is—

The design for a toy target, as shown.

SAMUEL HAMM.
